(57) **CLAIM**

The ornamental design for a pencil sharpener, as shown and described.

DESCRIPTION

FIG. 1 is a perspective view of the pencil sharpener;
FIG. 2 is a top view of the pencil sharpener;
FIG. 3 is a bottom view of the pencil sharpener;
FIG. 4 is a side view of the pencil sharpener (all sides are identical); and,
FIG. 5 is a sectional view taken along the lines 5-5 in FIG. 4.
The article is a pencil sharpener for sharpening pencils.
